UNITED STATES PATENT OFFICE.

ARTHUR E. COUPAL, OF SOUTH BOSTON, MASSACHUSETTS, ASSIGNEE TO BUFFALO SILE CO., OF BUFFALO, NEW YORK, A CORPORATION OF WEST VIRGINIA.

STAPLE MAKING AND DRIVING MECHANISM.

1,035,320.

Specification of Letters Patent. Patented Aug. 13, 1912.

Application filed July 22, 1911. Serial No. 449,987.

To all whom it may concern:

Be it known that I, ARTHUR E. COUPAL, a citizen of the United States, residing at South Boston, in the county of Suffolk and State of Massachusetts, have invented new and useful Improvements in Staple Making and Driving Mechanism, of which the following is a specification.

This invention relates to improvements in machines for forming staples from wire and driving them into the work and has for its object to provide means whereby when a staple is driven the points in clenching shall be bent toward each other and laterally with respect to the plane of the body of the staple so as to hold more firmly in the stock than has heretofore been possible.

To this end, my invention consists in the novel features of construction and in the combination and arrangement of parts set forth in the following specification and particularly pointed out in the claims.

Referring to the drawings: Figure 1 is a side elevation of a portion of the staple making and driving machine embodying my invention. Fig. 2 is an enlarged detail perspective view of the cutting and bending mechanism. Fig. 3 is a detail vertical section of the driver, throat and staple former and carrier as viewed from the front of the machine. Fig. 4 is a side elevation, partly in section, of the staple former and carrier, the throat and the driver, showing the throat in the position which it occupies after having descended to bend the staple. Fig. 5 is a sectional view taken on line 5-5 of Fig. 4, looking toward the left. Fig. 6 is a sectional view as seen from the front of the machine illustrating the throat, driver, work-plate and horn with the work supported thereon and showing the driver in the act of driving the staple. Fig. 7 is a detail front elevation of the upper or movable cutter. Fig. 8 is a front elevation of the upper and lower cutters, the upper cutter being partly broken away and shown in section, illustrating the co-operative action of the cutters upon the wire. Fig. 9 is a section taken on line 9-9 of Fig. 8. Fig. 10 is a detail plan of the blank after the same has been cut and illustrating the action of

the bender bending one of the points of the blank. Fig. 11 is an elevation of the completed staple before driving. Fig. 12 is an elevation of the staple as viewed from the right hand side of Fig. 11. Fig. 13 is an elevation of the staple as the same appears after being driven and clenched. Fig. 14 is an elevation of the staple viewed from the right hand side of Fig. 13.

Like numerals refer to like parts throughout the several views of the drawings.

In the drawings, 15 is a stationary cutter provided with a beveled face 16 terminating in a cutting edge 17 which extends diagonally across the line of travel A—A of the wire from which the staple blanks are to be made, the wire being guided along said path by a suitable guide 18. A movable cutter 19 carried by an actuating lever 20 is provided with an inclined face 21 in the same plane as the inclined face 16 of the stationary cutter 15 and is provided with a shoulder 22 arranged in the same plane with a vertical face 23 of the stationary cutter 15. In like manner, the stationary cutter 15 is provided with a shoulder 24 arranged in the same plane as a vertical face 25 of the movable cutter 19.

The movable cutter 19 is provided with a cutting edge 26 located in the plane of the surfaces 16 and 21, this cutting edge being concaved, as shown in Figs. 7 and 8, and inclined upwardly from the face 25 toward the shoulder 22 for a purpose which will presently appear. The shoulders 22 and 23 extend transversely of the longitudinal dimension of the wire and the faces 16 and 21 extend obliquely, as will be evident by an inspection of Fig. 9. Accordingly, the wire will be cut in the form shown in Fig. 10. When the cutter 19 descends, the lowermost portion of the cutting edge 26 engages the wire first and, owing to the concave shape of such cutting edge and its upward inclination, during the cutting of a staple blank 27, said cutting edge bends one end of said blank downwardly to form an inclined surface 28, as illustrated in Fig. 8, before the blank is completely severed from the body 29. During the latter part of the action of the cutters, the shoul-

der 22 descending upon the top of the wire forms at the extremity of the severed portion a rounded or beveled surface 30, as illustrated in Fig. 8. When the wire is fed 5 along the required distance to provide the necessary length for the staple blank and the movable cutter again descends, another blank is severed, and so on. In this way, there 10 is formed a staple blank 27 having substantially parallel oblique faces 31 and 32 which are to form the points of the prongs or legs of the staple. After each staple blank is severed from the body portion 29 of the wire, the right hand extremity of said body portion 15 is operated upon by a point bender 33 carried by a pivoted arm 34, said bender extending between the top face of the stationary cutter 15 and the under side of a stripper 35 which serves to prevent the blank 20 from rising with the movable cutter 19 when it ascends after the cutting operation. Thus it will be seen that by the action of the point bending device 33, when the staple blank is completed both points lie substantially in a 25 plane coinciding with one side of the staple blank, it being understood that the wire employed is substantially rectangular in cross section.

I have chosen to illustrate my invention 30 in connection with a machine of the class of which the machine of the patent to Cummings *et al.*, No. 493,910, dated March 21, 1893, is an example. I will now proceed to describe the mechanism by which the staple blanks are bent to form the staples and the staples are driven into the work, this mechanism being substantially the same as the mechanism for such purposes employed in connection with the patent to which I have 40 just referred.

36 is a staple former and carrier which is carried by a floating lever 37 which is carried forwardly and rearwardly at the proper times in the operation of the machine by a 45 link 38 connecting said lever to a cam lever 39 having journaled thereon a cam roll 40 located in a cam groove 41 formed in a cam 42 secured to a driving shaft 43 which is journaled in suitable bearings in the frame 50 44. A wire clamp 45 pivoted at 46 to the staple carrier and former 36 is provided at its front end with a notch 47 adapted to receive the wire, the front end of said clamp being pressed downwardly toward said carrier by means of a suitable spring 48. The staple carrier and former 36 is provided in its upper side with a bevel face 49 and the clamp 45 is provided near its lower side with a bevel face 50, which bevel faces converge toward each other toward the right hand side of the machine.

When the wire is fed through the wire guide 18 and across the top of the stationary cutter 15, said wire passes between the upper

side of the staple carrier and former 36 65 and the lower side of the clamp 45, the bevel faces 49 and 50 insuring the proper passage of the advancing end of the wire between the carrier 36 and clamp 45. After the wire has been fed the proper distance, 70 the carrier 36 and clamp 45 move rearwardly until the wire passes into the notch 47 so that when the wire is severed, as hereinbefore described, the severed portion which constitutes the blank from which the 75 staple is to be formed is held by said carrier and clamped at a point midway between the extremities of said blank. After the blank has been formed, the same is carried forwardly to a point beneath a throat 80 51 carried by a throat slide 52 arranged to reciprocate in suitable ways in a forwardly and rearwardly slideable head 53.

A vertical or reciprocatory movement is imparted to the slide 52 by means of a link 85 54 pivotally connected at its lower end to said slide and at its upper end to a bell crank lever 55 having journaled thereon a cam roll 56 located in a cam groove 57 formed in a cam 58 secured to the driving 90 shaft 43. The throat 51 is provided with a groove 59 in which a driver 60 is arranged to reciprocate, said driver being secured to a driver slide 61 to which a vertical reciprocatory motion is imparted by means of a 95 link 62 pivoted at its lower end to said slide and at its upper end to a bell crank-lever 63 having journaled thereon a cam roll 64 located in a cam groove 65 of a cam 66 secured to the driving shaft 43. The blank 100 being held by the clamp 45, as shown in Fig. 3, the throat 51 descends from the position shown in Fig. 3 to the position shown in Fig. 5, during which time the two sides of said throat act to bend the free 105 ends of said blank downwardly to form a staple, as shown in Fig. 5, the legs of said staple being held by frictional contact with the opposite sides of the groove 59. The staple carrier and former 36 and the clamp 110 45 then retreat or, in other words, move toward the left from the position shown in Fig. 4, thus leaving the staple held by frictional engagement with the opposite sides of the groove 59.

At the proper time in the operation of the machine, the throat 51 descends carrying the points of the staple into contact with or closely adjacent to the material into which the same is driven, after which the 120 driver 60 descends and drives the staple through the material, as shown in Fig. 6, the points of the staple being clenched against a horn 67. When the points of the prongs or legs of the staple strike the upper 125 end of the horn 67, said points, owing to the fact that they converge toward each other, turn inwardly toward each other, as illus-

trated in Fig. 13, and owing to the fact that both legs are beveled, as shown in Fig. 12, the points bend laterally with respect to the plane of the body of the staple, as illustrated in Fig. 14, and in this way, the prongs are clenched with an unusual degree of security, thus more firmly uniting the parts of the work to each other than has heretofore been possible.

10 The arm 34 which carries the point bending device 33 is pivoted on a stud which is secured to a shoe rest holder 34' and extends between a block 68, see Fig. 2, and a downwardly projecting part of an L-shaped arm 69, both of which are secured to the sliding head 53, there being a space between said block and the downwardly projecting part of the arm 69 greater in width than the width of the arm 34. As the sliding head 53 moves forward, the downwardly extending part of the arm 69 engages the rear face of the arm 34 and carries the latter, together with the bending device 33, forward, thereby causing the front end of said bending device to engage and bend the projecting part of the wire forward until its previously cut face lies in the plane of the front face of the wire, as hereinbefore described. Subsequently, when the sliding head 53 moves rearward, there is a lost motion between the block 68 and the arm 34 and finally said block brings up against said arm carrying the same backward at the proper time, thereby carrying the front face of the bender 33 back in line with the rear face of the wire.

The cutter carrying lever 20 receives its oscillating motion by suitable means such, for example, as a bell crank lever 70, see Fig. 1, having journaled thereon a cam roll 71 located in a cam groove 72 of a cam 73 secured to the driving shaft 43. By this mechanism, the movable cutter 19 is caused to descend at the proper time in the operation of the machine and sever a piece of the wire to form a suitable blank in the manner hereinbefore described.

Having thus described my invention, what I claim and desire by Letters Patent to secure is:

1. A staple machine having, in combination, means to cut a piece of wire to form a staple blank and bend said blank into the form of a staple, said cutting and bending means operating to make a staple provided with two legs, each having an outer inclined surface, the inclined surface of one of said legs inclined toward the inclined surface of the other of said legs and both of said inclined surfaces inclined toward a longitudinal plane extending laterally of a plane containing the median axial line of the wire constituting both legs of said staple, and means to drive said staples into the work

and clench the extremities of said legs toward each other and laterally of and on the same side of a plane passing longitudinally through the body of said staple. 65

2. A staple machine having, in combination, means to cut a staple blank from a piece of wire and bend both ends of said blank transversely of its longitudinal dimension, means to bend said blank into the form of a staple, said cutting and bending means operating to make a staple provided with two legs, each having an outer inclined surface, the inclined surface of one of said legs inclined toward the inclined surface of the other of said legs and both of said inclined surfaces inclined toward a longitudinal plane extending laterally of a plane containing the median axial line of the wire constituting both legs of said staple, and means to drive said staple into the work and clench the extremities of said legs toward each other and laterally of and on the same side of a plane passing longitudinally through the body of said staple. 70 75 80 85

3. A staple machine having, in combination, means to cut obliquely across a wire at two points to form a blank having parallel faces oblique to the longitudinal dimension of said blank and to bend one end of said blank laterally in the plane of one of said faces, means to bend the other end of said blank in a plane at right angles to the other of said oblique faces to bring the extremity of the latter end into alignment with the extremity of the first-mentioned end, means to bend said blank transversely thereof to form a staple provided with two legs having outer oppositely disposed surfaces inclined toward each other, and means to drive said staple into the work and clench the extremities of said legs toward each other and laterally of and on the same side of a plane passing longitudinally through the body of said staple. 90 95 100 105

4. A staple machine having, in combination, a pair of cooperating shearing cutters one of which is provided with a concave cutting edge whereby a piece of wire may be cut to form a staple blank having a laterally bent point at one end thereof, means to bend said blank into the form of a staple provided with two legs having outer oppositely disposed surfaces converging toward each other toward their extremities, and means to drive said staple into the work and clench the extremities of said legs toward each other and laterally with respect to the plane of the body of said staple. 110 115 120

5. A staple machine having, in combination, a pair of cooperating shearing cutters one of which is provided with a concave cutting edge lying in one plane and another cutting edge in a plane transverse to the first-mentioned plane, means to guide a wire between said cutters in a path oblique to the

first-mentioned plane, whereby said wire may be cut oblique to its longitudinal dimension and its extremities inclined toward one side thereof, means to bend said blank into the form of a staple provided with two legs having outer oppositely disposed surfaces inclined toward each other, and means to drive said staple into the work and clench the extremities of said legs toward each

other and laterally with respect to the plane 10 of the body of said staple.

In testimony whereof I have hereunto set my hand in presence of two subscribing witnesses.

ARTHUR E. COUPAL.
